UNITED STATES PATENT OFFICE.

ELWIN R. HYDE, OF BRIDGEPORT, CONNECTICUT, ASSIGNOR TO THE BRIDGEPORT SAFETY EMERY WHEEL COMPANY, INCORPORATED, OF BRIDGEPORT, CONNECTICUT, A CORPORATION OF CONNECTICUT.

SWING-FRAME GRINDER.

Application filed December 13, 1923. Serial No. 680,377.

To all whom it may concern:

Be it known that I, ELWIN R. HYDE, a citizen of the United States, residing at Bridgeport, county of Fairfield, State of Connecticut, have invented a new and useful 5 Swing-Frame Grinder, of which the following is a specification.

This invention relates to grinders and particularly to a swinging frame grinder, 10 and has for an object to provide a machine of this character which may be supported on a floor or suitable foundation, in which the grinding wheel will have universal adjustment and which grinder is so constructed that there are no supports or other 15 elements extending above a certain height to interfere with the passage of a travelling crane over the machine.

It is also an object of the invention to 20 provide a grinder in which the grinding wheel may be moved to practically any position desired and easily held therein by the operator.

With the foregoing and other objects in 25 view, I have devised the construction illustrated in the accompanying drawings forming a part of this specification, similar reference characters being employed throughout the various figures to indicate 30 corresponding elements. In these drawings,

Fig. 1 is a side elevation of the machine complete, a portion of the stand being broken away to more clearly show the construction.

Fig. 2 is a transverse section substantially 35 on line 2—2 of Fig. 1 on a somewhat enlarged scale.

Fig. 3 is a horizontal section substantially 40 on line 3—3 of Fig. 1, also on an enlarged scale.

Fig. 4 is an end elevation of the machine looking from the left of Fig. 1, and

Fig. 5 is a top plan view of the machine.

The machine comprises a base 10 adapted 45 to be mounted on a floor or a suitable foundation, and mounted upon this base to turn about a vertical axis is a support comprising a plate 11 and a pair of spaced uprights 12 mounted on this plate. The plate is pivoted to the base by an upright bolt or pin 13 about which the plate and the uprights 50 may turn, and to facilitate this turning movement both the plate and the top of the base are provided with a raceway for suit-

able balls 14 to provide a ball bearing between the two elements. The plate is also preferably provided with downwardly extending flange 15 with a ring 16 secured to the lower edge of this flange and extending under the flange 17 on the base to prevent 60 the support tipping laterally.

Extending transversely of the uprights 12 and between the same adjacent their upper ends is a bolt 18 forming a pivotal support for a frame 19. The bolt 18 preferably has 65 shoulders 20 adapted to engage the inner sides of the uprights so that when the nuts 21 are tightened the uprights will be securely clamped against these shoulders. The frame 19 comprises a pair of spaced members which extend on opposite sides of the bolt 18. It is normally in an upright position, as shown in Fig. 1, and is adapted to swing about the bolt 18 as a pivot. Below the pivot the frame carries a housing 22 70 which is mounted so as to swing in a vertical plane between the side members of the frame. This housing and the elements carried thereby is counter balanced by a suitable weight 23, carried by the frame 75 above its pivot.

The housing comprises a tube 24 to which are secured at its opposite ends suitable elements 25 and 26 having flanges 27 and 28 respectively. As a convenient means of 80 suitably mounting this tube in the frame 19 I provide a pair of clamping elements 29 which are adapted to embrace the tube on opposite sides thereof and which are clamped to the tube by suitable clamping 85 bolts 30 so that these elements are rigidly secured to the tube. Each element is provided with a trunnion 31 adapted to extend into a bearing in the side members of the frame 19 to form a pivotal support for 90 the housing and on which the housing may rock in a vertical plane. It will be apparent that by loosening the bolts 30 the clamping elements 29 may be adjusted to different positions on the tube to adjust the 95 balance of the housing and then clamped in adjusted positions. The elements 29 also have oppositely extending arms 32 extending above and below the tube provided with notches 33 in their outer ends to receive 100 tie rods 34. These tie rods are secured at their opposite ends to the flanges 27 and 28 and thus strengthen the tube and also re-

lieve it of a large part of the bending strains caused by the weight of the grinding wheel, its mounting and the motor for driving it.

Mounted at one end of the tube, as on the element 26, is a casing 35 in which is mounted a transverse shaft 36 carrying a suitable tool, as a grinding wheel 37. The shaft 36 is mounted in suitable ball bearings 38 and carries within the casing a bevel gear 39. The 10 grinding wheel is carried by the shaft outside the casing but the upper half of this wheel is enclosed in a guard 40 secured to the casing, as by the lateral extension 41. The casing is mounted on a sleeve 42 which 15 braces the element 26, as shown in Fig. 3, the casing being secured to the sleeve by suitable means, such as screws 43. The sleeve is adapted to turn on the element 26 to allow angular adjustment of the grinding wheel on 20 the housing. The sleeve is preferably slit, as shown at 44, and provided with a clamping screw 45 so that the casing may be either secured in a given position or the friction between the sleeve and the element 26 may be 25 adjusted to vary the resistance to turning of this sleeve on the element.

At the opposite end of the housing is mounted a supporting bracket 46, this bracket being preferably secured to the element 25, and mounted on this bracket is an electric motor 47. Connected with this motor and extending longitudinally through the tube 24 is a drive shaft 48, this shaft preferably running in ball bearings 49 in the tube and 30 at its opposite end carries a bevel gear 50 meshing with the bevel gear 39 so as to form a direct drive from the motor to the grinding wheel.

Carried by the casing 35 is a pair of spaced handles 51 which are preferably on opposite sides of the grinding wheel and so arranged that they may be grasped by an operator whereby he may move the grinding wheel to different positions and hold it against the surface to be ground. As a convenient means for mounting these handles I secure on one

50 handle, which in the present case is a piece of pipe, may be inserted. The handle is secured in the opening by a suitable set screw 52 having a series of vertically spaced openings 53 in any one of which the

55 handle is secured in these openings in the same way by set screws. It will be apparent from the foregoing description, that the grinding wheel may be moved to practically any position desired.

60 The operator by merely grasping the handles 51 may rock the housing in a vertical plane on the trunnions 31 so that the wheel may be either raised or lowered. It is to be noted that the wheel is counter balanced by the

lift any considerable weight. The wheel may also be moved toward and from the upright support in a horizontal plane by swinging the frame 19 about its pivot 18, and the housing with the wheel and motor are counter balanced by the weight 23. This swinging movement gives both up and down and horizontal movements to the wheel, and as the weight of the housing and the driving elements are counter balanced the wheel may be easily held in any desired position. The swinging movement of this frame may be limited by any suitable stops 57, these may be of any desired construction but are preferably substantially U-shaped metal straps 80 provided with openings 58 in the legs there- 85 means, of adapted to seat over pins 59 carried by the uprights 12. The stops are sufficiently flexible to allow the sides or legs to be sprung inwardly to remove them from the pins and allow them to be adjusted in different positions, the resiliency of the stops tending to maintain them on the pins. It will also be apparent that the grinding wheel may be 90 swung in an entire circle in a horizontal plane about the base 10, in addition to the

movements above described, and, furthermore, as the casing 35 is adapted to turn about the axis of the tube 24 the grinding wheel may be given any desired angular adjustment to grind surfaces placed on an angle. Thus the wheel may be adjusted to practically any position desired and held therein by the operator, and these adjustments may be easily and quickly made. Thus 100 in grinding heavy articles no setting up is required, the article being placed in the vicinity of the machine and then the wheel is moved to any desired position to grind as required. It is also especially to be noticed that there are no elements projecting above the weight 23 so that the space above the machine is entirely free, and there is nothing different to prevent passage of a travelling crane over

110 the machine.

Having thus set forth the nature of my invention, what I claim is:

1. In a grinder, a base, an upright support mounted on said base and adapted to turn about a vertical axis, an upright frame 115 pivoted in said support, a housing pivoted in the frame below the pivot for the frame, 54. Similar openings 55 are provided in an upright projection 56 on the guard 40 and a handle secured in these openings in the same way by set screws.

2. In a grinder, a base, an upright support mounted on said base and adapted to turn about a vertical axis, an upright frame pivoted in said support on a horizontal axis, a housing pivoted in the frame below the pivot for the frame, 120 125 130

3. In a grinder, a base, an upright support mounted on said base and adapted to turn about a vertical axis, an upright frame pivoted in said support on a horizontal axis, one end, a motor carried by the tube adjacent the other end, and a driving connection between the motor and wheel extending through said tube. 50
5. a housing pivoted in said frame on a horizontal axis located below the said pivot for the frame, a grinding wheel, a support for the wheel carried by the housing adapted for angular adjustment thereon, means for 55
- 10 clamping the support in different angular positions, a motor carried by the housing for driving said wheel, and one or more handles carried by the wheel support whereby it may be positioned and held during the 15 grinding operation.
4. In a grinder, a base, an upright support mounted on said base and adapted to turn about a vertical axis, an upright frame mounted to swing on a horizontal axis in 20 said support, a counter weight carried by said frame above said pivot, a housing pivoted in the frame below its pivot, a grinding wheel carried by the housing on one side of its pivot, a motor carried by the housing 25 on the other side of its pivot, and a driving connection between the motor and wheel.
5. In a device of the character described, a base, an upright support mounted on said base and adapted to turn about a vertical 30 axis, a frame mounted to swing in said support about a horizontal axis, a housing pivoted intermediate its length in said frame, a tool carried by the housing on one side of its pivot arranged for angular adjustment in said housing, means for clamping the tool in different adjusted positions, a motor carried by the housing on the other side of its pivot, and a driving connection 35 between the motor and tool.
- 40 6. In a grinder, an upright support, a pivoted frame in said support adapted to swing about a horizontal axis, a housing comprising a tube, supporting elements clamped to said tube intermediate its length on opposite sides thereof having trunnions pivoted in the frame and upright arms, tie rods extending over said arms and connected to the tube adjacent its opposite ends, a grinding wheel carried by the tube adjacent 45
- one end, a motor carried by the tube adjacent the other end, and a driving connection between the motor and wheel extending through said tube. 50
7. In a grinder, a support, a housing comprising a tube, supporting elements clamped to the opposite sides of the tube intermediate the ends thereof having trunnions pivoted in the support and upright arms, tie rods extending over said arms and secured to the tube adjacent the opposite ends thereof, a 55 bracket carried by the tube at one end thereof, a motor mounted on said bracket, a casing mounted at the other end of said tube, a transverse shaft mounted in the casing, a 60 grinding wheel mounted on said shaft, a shaft connected to the motor and extending longitudinally through the tube, and a driving connection between the two shafts. 65
8. In a grinder, a support, a housing comprising a tube pivoted intermediate its 70 length in said support, a bracket carried by the tube at one end, a motor mounted on said bracket, a casing carried by the tube at its opposite end and having a split bearing embracing the tube to turn on said tube, 75 means for clamping the bearing about the tube to hold the casing in different positions, a transverse shaft in said casing, a grinding wheel carried by said shaft, a shaft extending longitudinally through the tube and 80 connected with the motor, and a driving connection between the two shafts.
9. In a grinder, a base, an upright support mounted on said base and adapted to turn about a vertical axis, an upright frame 85 mounted to swing on a horizontal axis in said support, a counter weight carried by said frame above said pivot, a housing pivoted in the frame below its pivot, a grinding wheel carried by the housing on one side of its pivot and mounted for angular adjustment thereon, a motor carried by the housing on the other sides of its pivot, and a driving connection between the motor and wheel. 90

In testimony whereof I affix my signature.

ELWIN R. HYDE.
